Primary Examiner — Calvin E Vansant*Assistant Examiner* — Mark T. Philipp(74) *Attorney, Agent, or Firm* — Quickpatents, LLC; Kevin Prince(57) **CLAIM**

The ornamental design for an axial flow air/oil separator, as shown and described.

DESCRIPTION

FIG. 1 is a perspective view of an axial flow air/oil separator, showing my new design;

FIG. 2 is a perspective view of FIG. 1 with the axial separator element removed and placed alongside the main body for clarity;

FIG. 3 is a front elevational view of FIG. 2;

FIG. 4 is a rear elevation view of FIG. 2;

FIG. 5 is a left-side elevation view of FIG. 2;

FIG. 6 is a right-side elevation view of FIG. 2;

FIG. 7 is a top plan view of FIG. 2; and,

FIG. 8 is a bottom plan view of FIG. 2.

The broken lines depict portions of the axial flow air/oil separator that form no part of the claimed design.
